DESIGN FOR AN EVENING GOWN ENSEMBLE OR SIMILAR ARTICLE

Karen Stark, New York, N. Y.

Application September 21, 1940, Serial No. 95,250

Term of patent 3½ years

To the Commissioner of Patents:

Be it known that I, Karen Stark, a citizen of the United States, residing at Hyde Park Hotel, New York city, in the county of New York and State of New York, have invented a new, original, and ornamental Design for an Evening Gown Ensemble or Similar Article, of which the following is a specification, reference being had to the accompanying drawing, forming part thereof.

Fig. 1 is a front view of an evening gown ensemble showing my design;

Fig. 2 is a front view of the dress member of the ensemble shown in Fig. 1;

Fig. 3 is a rear view of Fig. 2, and

Fig. 4 is a rear view of the jacket member of the ensemble shown in Fig. 1.

I claim:

The ornamental design for an evening gown ensemble or similar article, substantially as shown.

KAREN STARK.
